UNITED STATES PATENT OFFICE

2,500,004

STRAND SPLICING DEVICE

Peter Nielsen, Omaha, Nebr., assignor to
Forrest R. King, Omaha, Nebr.

Application February 18, 1948, Serial No. 9,227

13 Claims. (Cl. 289—17)

1

This invention relates to improvements in tools for splicing the ends of line or strand material.

The primary object of this invention is the provision of a relatively simple practical tool which may be manufactured at relatively low cost; the purpose of which is to facilitate the splicing or knotting of the ends of flexible line or strand material such as gut, nylon, yarn, threads, etc.

A further object of this invention is the provision of an improved line splicing tool which may be utilized for the purpose of knotting the ends of line material, with knots such as described in U. S. Patent 2,488,414.

A further object of this invention is the provision of an easily handled portable tool which can be used by fishermen and others for the purpose of splicing flexible strands of line material together with non-slip knots.

Other objects and advantages of the invention will be apparent from the following detailed description.

In the accompanying drawings, forming a part of this specification, and wherein similar reference characters designate corresponding parts thruout the several views,

Figure 1 is a front view of the tool showing the knife side thereof.

Figure 2 is an edge view of the tool.

Figure 3 is a rear elevation.

Figure 4 is a cross sectional view taken longitudinally thru the tool on the center line of Figure 3.

Figure 5 is a perspective view showing an initial strand clamping operation.

Figure 6 is a perspective view showing a succeeding step in tying strands of material together.

Figure 7 is a perspective view of a further step in the tying operation.

Figure 8 is a perspective view showing an operator tying a different type of knot than that which is being produced in Figure 7.

Figure 9 is a view showing how the knot is pulled taut succeeding the operations shown in either of Figures 7 and 8.

Figure 10 is a view showing a splicing knot.

Figure 11 is a view showing another type of splicing knot.

Figure 12 is a view showing the application of the splicing knot upon the tool for the purpose of severing the loose ends of the strands after splicing.

Figure 13 shows the knife action in severing the loose ends.

Figure 14 is a front elevation of a knot modified

2

splicing tool including many of the characteristics of the tool of Figure 1.

Figure 15 is an edge elevation of the tool of Figure 14.

In the drawings, wherein for the purpose of illustration are shown different forms of the invention, the letters A and B may represent the preferred and modified forms of tools respectively shown in Figures 1 and 14. In each of these forms an improved knife arrangement C is provided having similar characteristics.

The tool A comprises an elongated flat body portion frame structure 10 of copper, brass, stainless steel. It may be of base metal which is plated with nickel or chromium, etc. It includes a lower handle portion 11 and an upper portion 12 wider than the handle portion. The latter flares at opposite sides 13 and 14 in a widening relation. The body 10 is preferably of uniform thickness thruout its length. At the extreme handle end 11 it is provided with an aperture 15 to facilitate handling. The top marginal edge 16 is convexly arcuated, or in lieu thereof the same may slope downwardly convergently from the medial axial line of the body.

Line or strand clamps 20 and 21 are provided upon the upper end of the body portion 10. They are relatively strong spring clamps and may take various forms. In the instance shown, each clamp includes a main clamping strip portion 22 provided with parallel right angled attaching ears 23 which lie at opposite side surfaces of the body portion 10 and are riveted to the latter at 24. The clamping strip 22 extends in close spring engaging relation with the top margin 16 of the body portion 10. Spaced from the ears 23 are a second smaller pair of ears 26 in engaging relation at each side of the body portion 10; these ears 26 having merely frictional sliding contact with the side surfaces of the body portion 10. The extreme spring clamping tip 30 of each of the clamps 20 and 21 is slightly turned upwardly from the top edge of the body portion 10. The tip ends 30 of the clamps 20 and 21 lie in close relation but are spaced at 31 so that the strands of material may be readily slipped under the tip ends 30 and beneath the clamping portions.

The body top 12 along its longitudinal, axial line is provided with a strand threading aperture 40 immediately below or adjacent to the clamps 20 and 21. A second pair of strand clamps 45 and 46 are provided upon the body portion 10 at opposite side surfaces of the latter. They consist of spring clamp arms riveted by a single rivet 47 along the medial axial line of the tool, but

the spring clamping arms 45 and 46 extend laterally in opposite directions; preferably convergently downward toward the handle end of the tool.

Referring to the knife structure C, the same includes a button-like knife disc 50 secured in sliding relation upon one side surface of the body portion 10 at the lower end of the upper portion 12. The means which secures it preferably consists of a screw or bolt 51 threaded thru a nut 52. The latter overlies the outer surface of the button 50 and has an extension projecting thru the central opening of the cutting disc 50. The body portion 10 is slotted at 53 to receive the attaching means for the cutting disc and this facilitates sliding of the cutting disc axially along the body portion 10, as is quite obvious. The body portion 10 is provided with a selection of openings 56, 57 and 58 which may be counter-recessed at one side of the tool body 10. The recessed side is adapted to receive the knot end of the strands and the loose ends are threaded thru the opening and project from the side along which the knife disc slides. The action of the knife disc is such that it may be positioned in the lower end of the slot 53 to uncover the apertures 56, 57 and 58 and then slid to the position shown in Figure 13 for severing loose ends of the spliced strands.

Referring to a description of the invention for splicing the strands or lines with a knot such as shown in Figure 10, the tool is held in the operator's hands, as shown in Figure 5, with the wide end upwards. The main portions of the lines or strands 70 and 71 to be spliced are positioned so as to bypass overlapping ends. The end portion of strand 71, designated at 71^a, is placed under the clamping tip 30 of the clamp 20 and the loose end 70^a of the strand or line 70 is placed under the tip end 30 of the other clamp 21. The length of the loose ends of the strands or lines may suit convenience since all slack is retrieved in the pull-up operation.

With the tool resting loosely in the hand, both thumbs of the operator's hands and forefingers are free for use in wrapping of the ends in either direction, at least two full turns over and under the main body line adjacent thereto. This is shown in Figure 6 of the drawings where the loose end 71^a is shown as having been wound over and under the main line portion of the adjacent strand 70 and then fed downwardly thru the V-shaped opening 80 and thru the threading opening or aperture 40. The loose end is then clamped under the spring clamp 45 at the opposite side of the body 10.

The above operation is repeated with the remaining loose end 70^a; the same being wound as above described around the main line 71, as shown in Figure 7 and then threaded downwardly thru the opening loop 80^a and thru the threading aperture 40. It is finally secured under the spring clamp 46. Care should be taken to guard against feeding the end of the second wrapping thru the loop of the first. The main lines 70 and 71 are then taken in the hands of the operator, as shown in Figure 9 and tool permitted to hang loose. Inasmuch as the loose ends 70^a are held by the clamps 45 and 46 the operator can urge the knot into place by pulling upon the lines, as is quite obvious. The loose ends are then freed from the keeper springs and the operator can snub the knot a little tighter with his thumb nails. The loose ends are then threaded thru the opening 57, or the other openings, depend-

ing upon the gauge of the line. The operator grasps the loose ends as shown in Figure 12 and the knot is pulled into the recessed side of the aperture, as close as desired. The thumb button 5 is then fed to the position in Figure 13 and this severs the loose ends. This produces a knot, such as shown at 90 in Figure 10 of the drawings.

To produce another type of knot, the lines are manipulated precisely the same as shown in Figures 5 and 6. However, instead of continuing as shown in Figure 7, the second loose end 70^a is wrapped around the main strand 71 and threaded upwardly thru the loop opening 80^b from below. It is then taken in the fingers and carried across over the top of a strand forming the loop (either one) and then is extended thru the aperture 40 and clamped at the opposite side. The knotting operation is the same as above described and shown in Figure 9. This will produce the type of knot shown at 91 in Figure 11 where the loose ends extends in opposite directions instead of parallel.

Insofar as applicable, the same reference characters are applied to the modified form of invention as above described for the preferred form A. The principal departure from the preferred form is that the upper portion 12^a of the body or frame structure of the tool is provided with integral spring clamping arms 20^a and 21^a which extend toward each other along the sloping edges 16^a and 16^b of the top margin of the tool. The tip clamping ends of the clamps are slightly upturned away from the edges 16^a and 16^b to provide entrance openings for the slipping of the strands of material under the clamping ends or tips 30^a. It is quite obvious that the knot tying operation can be accomplished with the tool B in the same manner as above described for the tool A.

Various changes in the shape, size and arrangement of parts of the improved appliance may be made, as well as departure from the steps of manipulating the various strands of material in the splicing of knots thereupon, without departing from the spirit of the invention or the scope of the claims.

I claim:

1. In an appliance for knot splicing the ends or flexible strands together the combination of an elongated flat body portion having a flattened upper marginal end edge provided with a plurality of line clamps thereon.
2. In an appliance for knot splicing the ends of lines or flexible strands together the combination of an elongated flat body portion having a flattened upper end edge provided with a plurality of line clamps thereon, and being provided with a threading aperture transversely through the body in position between said clamps.
3. In an appliance for knot splicing the ends of lines or flexible strands together the combination of a body portion having a flattened upper end edge provided with a plurality of line clamps thereon, and being provided with a threading aperture transversely therethrough between said clamps, and a plurality of other clamps on opposite sides of the body portion adjacent the said opening.
4. A portable tool for the tying of knots in flexible strands and lines comprising a flat elongated body portion having a pair of strand clamps on the extreme top marginal edge thereof, said body portion below and between said clamps having a transverse aperture therethru, and a clamp on each side of the body portion below said aperture.

5. As an article of manufacture a tool to facilitate the splicing of the ends of flexible strand or line material comprising a frame having a top marginal edge which slopes downwardly at each side of the medial axis of the frame, and relatively facing strand clamping springs mounted upon the top of the frame having spaced spring portions engaging the sloping edge at each side of the medial axis of the frame.

6. As an article of manufacture a tool to facilitate the splicing of the ends of flexible strand or line material comprising a frame having a top marginal edge which slopes downwardly at each side of the medial axis of the frame, and relatively facing strand clamping springs mounted upon the top of the frame having spaced spring portions engaging the sloping edge at each side of the medial axis of the frame, said frame below and between said clamps having a transverse strand threading aperture therethru.

7. As an article of manufacture a tool to facilitate the splicing of the ends of flexible strand or line material comprising a frame having a top marginal edge which slopes downwardly at each side of the medial axis of the frame, and relatively facing strand clamping springs mounted upon the top of the frame having spaced spring portions engaging the sloping edge at each side of the medial axis of the frame, said frame below and between said clamps having a transverse strand threading aperture therethru, and other clamps at each side of the frame below said threading aperture.

8. As an article of manufacture a tool to facilitate the splicing of the ends of flexible strand or line material comprising a frame having a top marginal edge which slopes downwardly at each side of the medial axis of the frame, and relatively facing strand clamping springs mounted upon the top of the frame having spaced spring portions engaging the sloping edge at each side of the medial axis of the frame, said frame below and between said clamps having a transverse strand threading aperture therethru, and other clamps at each side of the frame below said threading aperture, said last mentioned clamps extending in opposite directions for receiving strand ends at opposite sides of the medial axis of the frame.

9. A tool for splicing the ends of line material comprising a flat frame body having a handle end and a widened upper end, the widened upper end having a transverse strand threading opening therein, and spring clamps upon said widened upper end provided with clamping tips engaging the top margin of the widened upper end above and at opposite sides of the strand threading aperture.

10. A tool to facilitate the splicing of strand ends comprising a flat frame having a top margin which slopes downwardly at opposite sides of the medial line of the frame, and integral spring arms connected at their outer ends at opposite side margins of the frame and extending in facing relation towards each other and engaging the sloping top margin for spring clamping of strands thereunder.

11. A tool to facilitate the splicing of strand ends comprising a flat frame having a top margin which slopes downwardly at opposite sides of the medial line of the frame, and integral spring arms connected at their outer ends at opposite side margins of the frame and extending in facing relation towards each other and engaging the sloping top margin for spring clamping of strands thereunder, said frame between said spring ends having a transverse strand threading aperture.

12. A tool to facilitate the splicing of strand ends comprising a flat frame having a top margin which slopes downwardly at opposite sides of the medial line of the frame, and integral spring arms connected at their outer ends at opposite side margins of the frame and extending in facing relation towards each other and engaging the sloping top margin for spring clamping of strands thereunder, said frame between said spring ends having a transverse strand threading aperture, and a pair of strand clamping springs at opposite sides of the frame below said aperture.

13. In an appliance for the splicing of knots the combination of an elongated flat body portion having a handle at one end and a hand portion at the opposite end, a pair of clamps mounted upon said head portion including spring arms engaging the extreme marginal top edge of said head portion and in spaced relation, and a transverse aperture through said body portion adjacent to and between said springs.
